UNITED STATES PATENT OFFICE.

WILLIAM A. MCCOOL, OF BEAVER FALLS, PENNSYLVANIA, ASSIGNOR OF
ONE-HALF TO H. W. HARTMAN, OF SAME PLACE.

DRAWING METALS.

SPECIFICATION forming part of Letters Patent No. 400,238, dated March 26, 1889.

Application filed October 1, 1888. Serial No. 286,837. (No model.)

To all whom it may concern:

Be it known that I, WILLIAM A. MCCOOL, a citizen of the United States, residing at Beaver Falls, in the county of Beaver and State 5 of Pennsylvania, have invented certain new and useful Improvements in Machines for Drawing Metals; and I hereby declare the following to be a full, clear, and exact description of the same, reference being had to the accompanying drawings, wherein—

Figure 1 is a side elevation of a metal-drawing machine embodying my invention. Fig. 2 is a plan view of said machine. Fig. 3 is a vertical central longitudinal section of the 15 machine. Fig. 4 is an enlarged plan view of a portion of the box or tunnel, track, draft-chains, sprocket-wheel, grips, and die, the grips and die being partly in section, showing the rod to be drawn. Fig. 5 is an enlarged 20 view of one of the grips and its carriage. Fig. 6 is a similar view of the die, showing its attachment to the box or tunnel and the slots for the passage of the draft-chains. Fig. 7 is an enlarged detail view of one of the bearings 25 of a sprocket-wheel. Fig. 8 is a side view of the sectional grip-block or bushing; and Fig. 9 is a front or end view of the sectional grip-block, looking in the direction of the arrow, Fig. 8.

Like symbols refer to like parts wherever they occur.

My present invention relates to machinery for drawing metals, and may be broadly stated as one which combines two grips, an intermediate die, and power mechanism adapted to 35 actuate either grip, and the equivalent of the two grips may be generally stated as any grip device adapted to be used first to force the rod or like article into the die and then 40 draw the same through the die.

There are other minor features of construction, all of which will hereinafter appear.

I will now proceed to describe my invention more specifically, so that others skilled in the 45 art to which it appertains may apply the same.

Upon a foundation or bed-plate, A, are erected housings for any suitable driving-gear—such, for instance, as the band-wheel *b*, with friction-clutch *b'*, worm and worm-wheel 50 *c*, and cog-wheels *d* *e*, or their equivalents—by means of which power can be applied to a

traveling grip or set of grips. Extending therefrom are two side frames, B B, constituting an open box or tunnel forming a track, D D, for the carriages E E of the traveling 55 grips and a support or frame for the die-block C. At one end of said tunnel or box, on the shaft of the cog-wheel *e*, are sprocket-wheels *f f*, and at or near the opposite end thereof is journaled a shaft, *g*, having corresponding 60 sprocket-wheels, *h h*, while two parallel chain belts, *k k*, connect the said sprocket-wheels and are the preferred means for transmitting power to the traveling grips. The chain belts *k k*, arranged within the tunnel, may be supported at suitable intervals by rollers *l l*, so as to correct any sag thereof and relieve the power-shaft and tightening-shaft *g* of any unnecessary weight or strain, and the tightening-shaft *g* (of sprocket-wheels *h h*) may be 70 journaled in sliding bearings *m m*, (see Fig. 7,) if desired.

C indicates the die-block supported on the frames B B, and preferably secured thereto near one end thereof, as shown in Fig. 1. 75

The preferred detailed construction of the die-block and die is best understood from the enlarged view, Fig. 6, considered in connection with Fig. 4.

The die-block C may be a solid (or single) 80 casting sufficiently wide to extend from B to B, and provided with flanges by which it may be bolted to the frame; or it may be any other construction that circumstances dictate. It has a central circular aperture, *n*, 85 for the die, and two lateral apertures, *o o*, for the passage of the draft-chains *k k*. The die 1 may be of the tapering concentric solid-ring pattern, or any other approved form.

Mounted on track D D of frame B and 90 movable therein or thereon is a suitable grip truck or carriage, E, (see Figs. 4 and 5,) which, if desired, may be a single casting with journals (or journal-bearings) P P, for the wheels *w* thereof, or may be built in sections and 95 from any suitable material, if preferred. This carriage has a central grip-aperture, 3, having inclined sides (or tapering) for the reception of the tapering sectional grip 4; and in order to preserve the proper position of the 100 grip-sections in the holder (the truck) I prefer to employ keys and keyways or splines,

as indicated at *s*, Figs. 4 and 5. The interior of the grip may be faced or provided with bushing, as at *r r*, if desired.

At the sides of the grip-aperture, and usually in line therewith, are slots *t t* for the passage of the draft-chain belts *k k*, and intersecting said chain-slots are pin-slots *v v*, (see Fig. 4,) for the coupling-pins *V V*, (see Fig. 5,) by which the grip-carriage may be connected with the draft-chains *k k*, or equivalent source of power.

Two grips and grip-carriages are employed, one placed before and the other behind the die, and they will be found to be more efficient and workmanlike in construction if the structural differences shown in Fig. 4 are preserved, though it will be at once apparent that the difference between the construction of right-hand and left-hand grip of Fig. 4 is one of form and not of principle.

In order to actuate the grip, a lever, *5*, (see Fig. 3,) pivoted or having its fulcrum on the carriage, as at *6*, is provided with a pin, *7*, as indicated in dotted line, Fig. 5, which controls the sections of said grip *4* to release or withdraw said sections when the grip is to be shifted or loosened.

It will be noted that the form of grip shown is one having an unobstructed axial opening which will permit the free passage of a rod or bar of any length. This is a material feature of the grip where very long rods, bars, &c., are to be drawn, as it enables the grip to be shifted from time to time to renew its hold on the rods near the die, and it also enables the rod to pass through the grip as readily as through the die, and as continuously, which is a valuable feature in the first or entering grip.

The devices having the features hereinbefore described are operated by me as follows in carrying out my method: We will suppose the pins *V V* withdrawn from both carriages or trucks *E E*, power applied by means of the gearing to draft-chains *k k*, and said chains running free or without operating the grip-carriages. The rod, bar, tube, or other article to be drawn is passed through the grip of the first (or left-hand) carriage until its leading end projects therefrom a sufficient distance to pass through the die when the said first carriage has moved up to the die, and the grip of said carriage is then closed by means of the lever *5*, as before noted.

It is desirable that no excessive length of the leading end of the article should project, in order that there be no loss of power or tendency of the rod or bar to bend where unsupported by the die and grip. The pins *V* are then inserted and the first (or left-hand) carriage coupled to the power-chain, which causes the carriage to advance and force the end of the article into and through the die. The pins *V* are then withdrawn and the left-hand or first grip released, and the second (or right-hand) grip actuated by its lever *5* to seize the rod, bar, or other article on the opposite side of

the die, after which the second (or right-hand) grip-carriage is coupled to the power and the article drawn in the usual way. In case of long rods the unobstructed axial opening of the die and the arrangement of the power mechanism permit the second or draft grip to be shifted from time to time, so as to renew its hold on the rod near the die, whereby any continuous length of rod may be drawn without interrupting the operation of the machine but momentarily. Further, the character of the grip is such that after the left-hand or first grip has performed its function as an entering grip it becomes a guide, and therefore is not inoperative or useless thereafter, as many other forms of grip which might be used would be.

Having thus described the nature and advantages of my invention, what I claim, and desire to secure by Letters Patent, is—

1. The combination, with a fixed drawing-die, of grip mechanism adapted to first force and then pull the article operated on, substantially as and for the purposes specified.

2. The combination, with two grips, of an interposed fixed die and mechanism for actuating the grips, substantially as and for the purposes specified.

3. The combination, with a fixed drawing-die, of a grip having an unobstructed axial opening throughout its length, and power mechanism for actuating said grip, said power mechanism arranged at one side, or off the axial or center line of the die and grip, whereby the hold of the grip on the rod being drawn may be advanced from time to time to draw continuous rods of any desired length, substantially as specified.

4. The combination, with two grips, each of which has an unobstructed axial opening throughout its length, of an interposed die, substantially as and for the purposes specified.

5. In a metal-drawing machine, the combination, with a grip-truck having a tapering annular orifice or grip-seat, of a tapering annular sectional grip, substantially as and for the purposes specified.

6. In a metal-drawing machine, the combination, with a grip-truck having a tapering grip-seat, of a tapering sectional grip, a grip-lever having a fulcrum on the truck, and a pin for actuating the grip-sections, substantially as and for the purposes specified.

7. The combination, with a fixed drawing-die, of a pushing-grip arranged in front of said die, and power mechanism for actuating said grip, substantially as and for the purposes specified.

In testimony whereof I affix my signature, in presence of two witnesses, this 24th day of September, 1888.

WILLIAM A. MCCOOL.
